(57) **CLAIM**

The ornamental design for a flowerpot, as shown and described.

DESCRIPTION

FIG. 1 is a top front perspective view of the flowerpot of the present invention;

FIG. 2 is a front view, the rear view being a mirror image thereof;

FIG. 3 is a left side view, the right side view being a mirror image thereof;

FIG. 4 is a top view thereof; and,

FIG. 5 is a bottom view thereof.

The portions of the flowerpot illustrated in broken lines form no part of the claimed subject matter.
